(57) **CLAIM**

The ornamental design for a sealant bottle cap, as shown and described.

DESCRIPTION

FIG. 1 is a perspective view of the sealant bottle cap, according to the invention;

FIG. 2 is a front view of the sealant bottle cap shown in FIG. 1;

FIG. 3 is a rear view of the sealant bottle cap shown in FIG. 1;

FIG. 4 is a side view of the sealant bottle cap shown in FIG. 1;

FIG. 5 is a side view, opposite the side view shown in FIG. 4, of the sealant bottle cap shown in FIG. 1;

FIG. 6 is a top view of the sealant bottle cap shown in FIG. 1; and,

FIG. 7 is a bottom view of the sealant bottle cap shown in FIG. 1 with the environmental bottle removed for ease of illustration.

The dash-dash broken lines are included for the purpose of illustrating environmental structure and form no part of the claimed design.

1 Claim, 7 Drawing Sheets
